(57) **CLAIM**

The ornamental design for a hair styling tool, as shown and described.

DESCRIPTION

FIG. 1 is a top view of a hair styling tool showing our new design;

FIG. 2 is a bottom view thereof;

FIG. 3 is a front view thereof;

FIG. 4 is a rear view thereof;

FIG. 5 is a top perspective view thereof;

FIG. 6 is a bottom perspective view thereof;

FIG. 7 is a side view thereof;

FIG. 8 is a second side view thereof;

FIG. 9 is a second top perspective view thereof;

FIG. 10 is an enlarged bottom perspective view of the handle end thereof;

FIG. 11 is an enlarged top perspective view of the handle end thereof;

FIG. 12 is an enlarged perspective view of the electrical-connection collar of the hair styling tool of FIG. 1, shown separately to reveal aspects of the design that may not be apparent in other figures;

FIG. 13 is an enlarged top view thereof;

FIG. 14 is an enlarged bottom view thereof;

(Continued)

FIG. 15 is an enlarged front view thereof;
 FIG. 16 is an enlarged rear view thereof;
 FIG. 17 is an enlarged first side view thereof; and
 FIG. 18 is an enlarged second view thereof.
 The grayscale coloring in FIGS. 1-18 represent color contrast. No particular color is being claimed.
 The dash-dot lines in FIGS. 12-18 depict boundaries of the claim and the lines themselves form no part of the claimed design.
 The evenly dashed lines in FIGS. 12-18 illustrate features of the electrical connection collar of the hair styling tool that form no part of the claimed design.
